FLORAL STAND

Robert S. Terrell, 7800 Bodega Highway,
Sebastopol, Calif.

Filed Apr. 22, 1964, Ser. No. 79,652

Term of patent 14 years

(Cl. D35—3)

Fig. 1

Fig. 2

FIG. 3

FIG. 4

FIG. 1 is a perspective view of a floral stand showing my new design;

FIG. 2 is a top view of the floral stand of FIG. 1;

FIG. 3 is a side view of the floral stand of FIG. 1; and

FIG. 4 is a fragmentary perspective view thereof.

The broken lines disclosed in FIG. 4 are for illustrative purposes only.

I claim:

The ornamental design for a floral stand, as shown and described.
